UNITED STATES PATENT OFFICE.

GEORGE T. BUDDLE, OF CHICAGO, ILLINOIS.

COMBINED TABLE LOCK AND OPENER.

1,156,461.

Specification of Letters Patent.

Patented Oct. 12, 1915.

Application filed October 30, 1914. Serial No. 869,438.

To all whom it may concern:

Be it known that I, GEORGE T. BUDDLE, a citizen of the United States, residing at Chicago, in the county of Cook and State of Illinois, have invented a new and useful Combined Table Lock and Opener, of which the following is a specification.

This invention relates to locks for use in connection with extension tables and is more especially a lock of that type disclosed for example in Patent No. 1,103,029, issued to me on July 14, 1914.

One of the objects of the invention is to provide a lock of few parts, which can be applied readily to a table or the like, and which, when moved in one direction, to operate to unlock the parts of a table top and to shift said parts relative to each other and which, when moved in the opposite direction, will operate successively to engage the movable part of a table top and draw said part toward the adjacent fixed part of the top.

A further object is to provide a lock of this character utilizing a latch of novel form having a combined guide and tripping element whereby the latch is actuated at the proper time during the operation of the lock.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings:—Figure 1 is a bottom plan view of a portion of an extension table having the present improvements combined therewith, the sections of the table being shown drawn together. Fig. 2 is a similar view but showing the sections of the table unlocked and pushed apart. Fig. 3 is a bottom plan view of a modified form of lock, the parts being shown held together. Fig. 4 is a similar view showing the parts unlocked and pushed apart. Fig. 5 is a section on line A—B Fig. 1.

Referring to the figures by characters of reference C and D designate opposed sec-

tions of an extension table or the like and secured to one of the sections is a keeper made up of a base or attaching plate 1 and an outstanding ear 2, the ear extending only partly across the base or attaching plate. Secured to the section D is an attaching plate 3 having an eye 4 outstanding therefrom and slidably mounted within this eye is a latch strip 5, one end of which is pivotally connected, as at 6, to a lever 7 fulcrumed, at 8, upon an attaching plate 9 secured to the section D. This plate has a lug 10 projecting therefrom and constituting a stop for limiting the movement of the lever 7 in one direction.

The latch strip 5 is provided at one end with a tongue 11 at one side of which is arranged a shoulder 12 adapted to bear against the ear 2 of the keeper, the tongue 11 being designed to extend past the ear 2 as shown in Fig. 2.

Pivoted on the strip 5 is a latch 13 provided, at its outer end, with a hook 14, while extending laterally from its inner end portion is a nose or projection 15. The latch 13 extends into the eye 4 and the pivot stud 16 on which the latch is mounted is adapted to work within a recess 17 formed within the eye, as shown particularly in Fig. 5.

The nose or projection 15 is so positioned that, when the latch is projected in one direction, the said nose or projection will strike against the eye 4. Consequently it will be apparent that during the movement of the lever 7 in the direction indicated by the arrow in Fig. 1, the shoulder 12 of the latch strip 5 will be brought against the ear 2 and will push against said ear so as thus to move the sections apart. During the completion of this movement, the nose 15 comes against the eye 4 and causes the latch 13 to swing about its pivot 16, thus swinging the hook 14 laterally from back of the ear 2 and to the position shown in Fig. 2. Consequently section D can be pushed from section C.

When it is desired to assemble the sections C and D, the section C is pushed toward the section D, thus to bring the ear 2 against the shoulder 12. By then swinging lever 7 in a direction opposite to that indicated by the arrow in Fig. 1, the side of the latch 13 will work against the eye 4 so that said latch will be shifted laterally to bring the hook 14 back to the ear. Thus the hook will

engage said ear and, during the continued movement of the latch strip 5, the section C will be drawn tightly against the section D.

Instead of providing a keeper having a single ear which receives both the thrust exerted by the shoulder 12 and the pull exerted by the hook 14, a keeper having separate ears 18 and 19 can be provided, as shown in Figs. 3 and 4. Where a keeper of this form is employed, the tongue 20 upon the latch strip 21 is made longer than the tongue 11 so as to project beyond the hook 22 on latch 23. Furthermore the shoulder 12 is dispensed with. Thus it will be seen that when the latch strip 21 is shifted in one direction, the end of tongue 20 will move against the ear 19 and push the sections apart, after which the nose 24 on the latch will strike the guide eye 25 and cause the hook 23 to be shifted from back of the ear 18. During the movement of the latch strip 21 in the opposite direction, the latch 23 will operate in the manner hereinbefore described so as to engage ear 18 and pull the two sections together.

What is claimed is:—

1. The combination with a keeper having a projecting ear, of a guide member, a slid-

able member within the guide member, means for shifting said slideable member in one direction to push against the keeper, a keeper engaging latch pivotally connected to the slideable member, and means upon the latch and coöperating with the guide for shifting said latch out of engagement with the keeper during the completion of the pushing movement of the slideable member.

2. The combination with a keeper, of a guide member, a slideable member within the guide member, means for shifting the slideable member in one direction to push against the keeper, a keeper engaging latch pivotally connected to the slideable member, and a projecting portion upon the latch and movable against the guide during the pushing movement of the slideable member to shift the latch out of engagement with the keeper.

In testimony that I claim the foregoing as my own, I have hereto affixed my signature in the presence of two witnesses.

GEORGE T. BUDDLE.
